UNITED STATES PATENT OFFICE.

FREDERICK D. RICH, OF SALISBURY, ASSIGNOR OF ONE-HALF TO NATHAN D. DODGE, OF NEWBURYPORT, MASSACHUSETTS.

MACHINE FOR SLASHING INNER SOLES.

SPECIFICATION forming part of Letters Patent No. 438,643, dated October 21, 1890.

Application filed July 28, 1890. Serial No. 360,170. (No model.)

To all whom it may concern:

Be it known that I, FREDERICK D. RICH, of 5
Salisbury, in the county of Essex and State
of Massachusetts, have invented new and
useful Improvements in Machines for Slashing
Inner Soles of Boots and Shoes, of which
the following is a specification.

This is a machine for rendering boot and
shoe inner soles more flexible by making a
series of slashes or incisions in the surface
thereof. These cuts or incisions are made
transversely and on a slant, whereby a greater
depth of the cut may be obtained, and hence
proportionately greater flexibility, and they
are produced by a gang of reciprocating cutters
or knives operated by a machine constructed
substantially as below set forth, and
illustrated in the accompanying drawings, in
which—

20 Figure 1 is a plan view of a machine em-
bodying my invention. Fig. 2 is a side ele-
vation of the same with the cutters and cut-
ter-head in vertical section. Fig. 3 is an en-
larged horizontal section, in detail, of a por-
25 tion of the cutter-head, showing the method
of securing the cutters in place. Fig. 4 is a
sectional detail showing the mechanism for
limiting the throw. Fig. 5 is a rear elevation
of the machine. Fig. 6 is a plan of an inner
30 sole rendered flexible by having been cut or
slashed by this machine.

Similar letters of reference indicate like
parts.

A represents a bed, preferably metallic, to
35 which are bolted the uprights B B, which,
with the cross-piece C, constitute the frame
of the machine.

D is the driving or actuating shaft, sup-
ported in the frame by means of boxes d and
40 operated by a hand-lever D' or other means
or power. Extending up from and integral
with this shaft D are a pair of levers E E, to
whose free ends are pivotally secured the
lower ends of the links or bars F F, their up-
45 per ends being secured to the opposite ends
of a horizontal rod G, which extends through
a hole H' in the upper end of the reciprocating
cutter-bar or plunger H. This bar H lies and
fits in an opening or hole C'', made at an an-
gle of, say, forty-five degrees in the tubular
50 central and guiding portion C' of the cross-
piece C.

I is the cutter-head, adjustably secured by

a set-screw e or other suitable means to the
lower end of the plunger H. The lower end 55
or foot I' of this cutter-head is grooved on its
under side transversely to receive a gang of
cutters K, said grooves and cutters being
made and set on a line with the plunger, so
that they are on a slant or angle of, say, forty- 60
five degrees with the bed A. The knives are
held in place removably by graduated pins
or plugs J, Fig. 3, so that knives or cutters
of various sizes may be employed.

In operation the sole S is placed in proper 65
position beneath the cutter-head, whose posi-
tion when raised is shown in Figs. 2 and 5.
The lever D' is swung forward, producing
partial rotation of the shaft D, and the levers
E on said shaft, by means of the links F, force 70
down the plunger H, guided by the portion C'
of the cross-piece into the position shown in
broken lines in Fig. 2, thus producing the
slanting cuts or slashes S' in the sole. Re-
versing the lever D' of course raises the plun- 75
ger into its former position. The movement
or throw of the plunger (and knives) down-
ward is adjustably limited by means of the
set-screws l in the stops or projections L in-
tegral with the cross-bar C, said set-screws 80
being struck by the levers E, (see Figs. 1, 2,
and 4,) and the movement back is limited by
the set-screw n in a downward stop or exten-
sion N of the cross-bar C, said set-screw being
struck by the lug P, extending down from 85
one of the levers E. (See Figs. 2, 4, and 5.)

Having thus fully described my invention,
what I claim, and desire to secure by Letters
Patent, is—

The herein-described machine for render- 90
ing boot and shoe soles more flexible by cut-
ting or slashing the surface thereof, comprising
the shaft D, supported in the frame, the
levers or cranks E, links F, and rod G, the
plunger H, provided with the cutter-head I 95
and gang of cutters K, and the guiding cross-
piece C, provided with the central hole C''
for guiding the plunger, said plunger and
cutters being set at a slant with the surface
of the shoe-sole, whereby a series of slanting 100
incisions or cuts are produced therein, sub-
stantially as described.

FREDERICK D. RICH.
